INVENTOR.

UNITED STATES PATENT OFFICE.

GAETANO ZITO, OF NEW YORK, N. Y.

TOY.

1,284,544.

Specification of Letters Patent. Patented Nov. 12, 1918.

Application filed September 20, 1917. Serial No. 192,310.

To all whom it may concern:

Be it known that I, GAETANO ZITO, a citizen of the United States, residing at New York, in the county of the Bronx and State 5 of New York, have invented certain new and useful Improvements in Toys, of which the following is a full, clear, and exact specification.

My invention relates to new and useful 10 improvements in mechanical toys, and has for its principal object to provide a toy particularly adapted for the amusement of children, the mechanism of the toy being simple in character, of a novel nature, and inexpensive to manufacture.

Among other features, my invention contemplates a toy which consists of relatively movable members, preferably horses, having relatively movable figures mounted thereon, 20 preferably cavalry soldiers, known as lancers, the said horses being pivotally connected to a fixed supporting rod as well as a sliding supporting rod, and all of which members, when the said rods are manipulated during the operation of the device, will produce an amusing result representing the lancers engaged in a contest of skill or in deadly combat.

With these and other objects in view, my 30 invention consists in the novel combination and arrangement of parts, and all of which will be fully set forth in the following specification and accompanying drawing, in which—

35 Figure 1 is a front elevation of the device showing the same in normal position.

Fig. 2 is a sectional front elevation, showing the horses as well as the riders in one of the positions assumed, in the operation of 40 the device; and

Fig. 3 is a vertical transverse sectional view, taken substantially on the line 3—3 in Fig. 2, showing generally the manner of mounting the various movable members and 45 the coöperating figures.

The embodiment of my invention shown in the drawing, comprises a plurality of movable members 1 and 2, representing horses, the front legs 3 and 4 of which are 50 pivotally connected to a supporting rod 5 at the places marked 6, and which rod is held in fixed position by the handle 7 and the blocks or posts 8, as shown in Fig. 1. The back legs 9 and 10 of the horses 1 and 2 are 55 pivotally connected to the supporting rod 11 at the places marked 12 and 13 and which

rod 11 is held in slidable engagement by the handle 7 and the blocks or posts 8, and is moved backward and forward through the opening 14 in said handle and the openings 15 in said blocks, for the purpose of operating the device, as hereinafter explained. The front legs 3 and 4 of the horses 1 and 2 are pivotally connected to the bodies of said horses at the places marked 60 16; and, likewise, the back legs 9 and 10 of said horses are also pivotally connected to the bodies of the horses at the places marked 17. Upon the horses 1 and 2 are mounted figures 18 and 19, representing cavalry soldiers provided with lances 20, held in fixed position by any suitable fastening means underneath the arms 21 and 22 of the respective riders, at the places marked 23. The riders 18 and 19 are held in fixed position upon the horses 1 and 2, by any suitable fastening means, at the places marked 24. The bodies of the riders are pivotally connected to their thighs at the places marked 25, and the arms 21 and 22 of the said 70 riders are also pivotally connected to the bodies of the riders, at the places marked 26. During the operation of the device, when the sliding supporting rod 11 is moved backward and forward, through the opening 14 75 of the handle 7 and the openings 15 in the blocks 8, the horses 1 and 2, by reason of their pivotal connections to the said rod 11, as well as to the rod 5, will also move backward and forward, assuming various 80 positions, and thereby producing a jumping or galloping movement. To prevent the horses, when the toy is in operation, from assuming a flat position on the supporting rod 5, a slight projection is provided on 90 the underside of the bodies of the horses 1 and 2, at the places marked 27, as shown in Fig. 2, and against which projection bolts 28, passing through the rear legs 9 and 10 of the horses, abut. In order to cause the 100 bodies of the riders 18 and 19, as well as the arms 21 and 22, respectively of said riders, to assume various positions when the horses 1 and 2 are moved backward and forward, during the operation of the device 105 as just described, two sets of bands 29 and 30 of rubber, or other suitable material, are provided; one set of bands 29 are fastened by any suitable fastening means to the lower ends of the bodies of the said riders at the 110 places marked 31 and also to the bolts 32, between the front legs 3 and 4 of said horses.

115

and which bolts pass between said legs, as illustrated in Fig. 2. The other set of bands 30 are fastened by any suitable fastening means to the hands of the respective 5 riders at the places marked 33, these bands passing through the mouths 34 of the horses 1 and 2, and representing reins.

As above explained, in the operation of the device, it will be seen that when the operator pushes the slideable supporting rod 11 backward and forward, this will cause the horses 1 and 2 to move backward and forward, and by reason of this movement, together with the two sets of bands 29 and 30, 15 of rubber or other suitable material, the bodies as well as the arms of the respective riders 18 and 19 mounted on said horses, will sway backward and forward and assume various positions, and one of which is shown 20 in Fig. 2 of the drawing.

In the operation, it is, of course, understood that the operator will hold the handle 7 firmly in one hand and manipulate the rod 11 with the other hand; and when the said 25 rod is moved backward and forward rapidly, the result of such movement gives the impression to the operator that the riders, mounted upon their respective horses, are thrusting their lances at one another and engaged either in a contest of skill or in mortal 30 combat, thereby producing an amusing as well as interesting entertainment for children. It is, of course, understood that any suitable springs, spiral or otherwise, may be 35 substituted for the two sets of bands 29 and 30 above mentioned; and it is obvious that the invention is susceptible of changes or variations in the constructional details thereof, without therefore departing from the spirit 40 of the invention, or the scope of the appended claims.

I claim:

1. In a toy, a plurality of fixed and slideable supporting members; a plurality of figures, representing horses, carried by said members; a plurality of figures, representing persons, mounted on said horses; and means for actuating all of said members, with the exception of the fixed supporting members.

2. In a toy, a fixed supporting member; a slideable supporting member; means for supporting said members; a plurality of figures, representing horses, having pivotal connections with said supporting members; a plurality of figures, representing persons, pivotally mounted on said horses; and means for actuating all of said members, with the exception of the fixed supporting member.

3. In a toy, a fixed supporting member; a slideable supporting member; a handle and a plurality of blocks for supporting said supporting members; a plurality of figures, representing horses, each having independent 65 pivotal connection with said supporting

members; a plurality of figures, representing persons, carried by said horses, each having independent pivotal connection with said horses; and manually operated means for actuating all of said members, with the exception of the fixed supporting member.

4. In a toy, the combination of a handle; a plurality of blocks; a fixed supporting member carried by said handle and said blocks; a slideable supporting member also 75 carried by said handle and said blocks; a plurality of figures, representing horses, carried by said supporting members; a plurality of figures, representing persons, mounted on said horses; and means for actuating all 80 of said members, with the exception of the fixed supporting member.

5. In a toy, the combination of a handle; a plurality of blocks; a fixed supporting member and a slideable supporting member 85 carried by said handle and said blocks; a plurality of figures, representing horses, each having independent pivotal connection with the said supporting members; a plurality of figures, representing persons, carried by said horses and each having pivotal connection with said horses; and means for actuating all of said members, with the exception of the fixed supporting member.

6. In a toy, the combination of a plurality 95 of figures, representing persons, provided with arms pivotally connected to the bodies of said persons; a plurality of figures, representing horses, provided with legs pivotally connected to the bodies of said horses, 100 and to the bodies of which horses the said persons are also pivotally connected; a fixed supporting rod; and a slideable supporting rod for supporting said horses; means for supporting said rods; and means for actuating all of said members, with the exception of the fixed supporting rod.

7. In a toy, the combination of a handle; a plurality of blocks; a fixed supporting member and a slideable supporting member 110 supported by said handle and said blocks; a plurality of figures, representing horses, each having independent pivotal connection with said supporting members; a plurality of figures, representing persons, each having independent pivotal connection with said horses, the said persons having arms pivotally connected to their bodies; means for actuating said arms; means for actuating said bodies; and means for actuating all of 115 said members, with the exception of the fixed supporting member.

8. In a toy, the combination of a handle; a plurality of blocks; a fixed supporting member and a slideable supporting member 125 supported by said handle and said blocks; a plurality of figures, representing horses, each having independent pivotal connection with said supporting members; a plurality of figures, representing persons, each having 130

independent pivotal connection with said horses, the said persons having arms pivotally connected to their bodies; means for actuating said arms; means for actuating said bodies; means for limiting the backward movement of said bodies; means for limiting the backward movement of said horses; and means for actuating all of said members, with the exception of the fixed

10 supporting member.

9. In a toy, a plurality of movable members, representing horses, provided with legs pivotally connected to the bodies of said horses; a fixed supporting rod and a slidable supporting rod carrying the said horses and to which horses the said rods are pivotally connected; means for supporting said rods; a plurality of figures, representing persons, pivotally connected to the bodies of

20 said horses, said persons being provided with arms also pivotally connected to their bodies; means for swaying backward and

forward the bodies of said figures as well as the arms of said figures; and means for actuating all of said members, with the exception of the fixed supporting rod. 25

10. In a toy, the combination of a plurality of supports, one fixed and the other movable; a handle for holding said supports in fixed and slidable engagement; a plurality of objects, composed respectively of various pivotally connected members and which objects are pivotally connected to the fixed and movable supporting members, whereby when the movable member is actuated said objects will assume various positions. 30 35

In testimony whereof, I affix my signature, in presence of two witnesses.

GAETANO ZITO.
